UNITED STATES PATENT OFFICE.

WATSON B. STOCKMAN, OF CHESTER, PENNSYLVANIA.

DILUTING DEVICE FOR INTERNAL-COMBUSTION ENGINES.

Application filed December 21, 1921. Serial No. 523,964.

To all whom it may concern:

Be it known that I, WATSON B. STOCKMAN, citizen of the United States, residing at Chester, in the county of Delaware and State of Pennsylvania, have invented certain new and useful Improvements in Diluting Devices for Internal-Combustion Engines, of which the following is a specification.

10 This invention relates to an improved diluting device for internal combustion engines and seeks, as one of its principal objects, to provide a device of this character whereby either hot or cold air may, as desired, be introduced into the fuel mixture.

A further object is to provide a device wherein, when the throttle valve of the engine is closed, air may be fed into the engine cylinders so that the ensuing compression therein may be used to brake the engine while the engine will be coincidentally cooled.

A still further object is to provide a device employing a throttle valve governing the flow of both hot and cold air.

25 The invention has as a still further object to provide a device employing an air throttle valve automatically operable for varying the rate of feed of air to the fuel mixture as well as controlling the supply of air to the engine cylinders when the engine throttle valve is closed.

30 And the invention has as a still further object to provide a device employing an improved distributor for introducing air into the fuel mixture.

35 Other and incidental objects will appear hereinafter.

In the drawings:

Figure 1 is a fragmentary side elevation showing my improved device in connection with a motor vehicle engine of conventional design,

40 Figure 2 is a fragmentary perspective view showing the valves of the device and associated parts,

Figure 3 is a longitudinal vertical sectional view through the valves,

45 Figure 4 is a sectional view on the line 4-4 of Figure 3, looking in the direction of the arrows,

Figure 5 is a sectional view through the distributor of the device,

50 Figure 6 is a detail perspective view showing the throttle lever arm of the device,

55 Figure 7 is a view partly in plan and partly in section, showing the position of

the air throttle valve of the device when the fuel throttle valve of the engine is closed,

Figure 8 is a view similar to Figure 7, showing the air throttle valve moved to open position when the fuel throttle valve is closed, and

Figure 9 is a fragmentary perspective view showing a slightly modified form of control valve.

Referring now more particularly to the drawings, I have, for convenience, shown my improved device in connection with the engine 10 of a conventional motor vehicle. The intake manifold of the engine is indicated at 11 and associated with said manifold is the engine carburetor 12 having the usual throttle valve lever 13 equipped at its inner end with a stop screw 14 to coact with a post 15 for limiting the valve in its movement to closed position. The exhaust manifold of the engine is indicated at 16 while the vehicle steering post is indicated at 17.

Coming now more particularly to the subject of the present invention, I employ a heater 18 which, as shown in Figure 1, is rested upon the exhaust manifold 16 of the engine so as to be heated thereby. This heater may be secured upon the manifold in any appropriate manner and extending from the heater is an air pipe 19 preferably covered with some suitable heat insulating material. Connected to the lower end of this pipe is a control valve which, as shown in Figure 2, is formed with a squared valve body 20 provided at opposite sides thereof with alined nipples 21 and 22 while in one side of the valve body is formed a cold air inlet 23. As will be observed, the pipe 19 is attached to the nipple 21 and slidably through the valve body is a squared control valve 24 through which is formed, as shown in Figure 3, a straight passage 25 and a second passage 26 having angularly disposed portions opening through one side of the valve and the bottom face thereof. When the opening 25 of the valve is brought into register with the passages of the nipples 21 and 22 of the valve body, hot air will then be permitted to flow through the valve from the heater 18 while, when the valve is shifted to move the passage 26 into register with the cold air inlet 23 of the valve body, cold air will then flow through the valve, the flow of hot air being cut off.

Projecting 105 forwardly from the valve body at one side thereof is an arm 27 provided at its outer

- end with a laterally directed lug 28 and threaded at one end through this lug is a flexible cable 29 which, as shown in Figure 1, is directed around the forward end of the 5 engine block and is then arranged to extend upwardly along the steering post 17. Connecting the upper end of the cable with the steering post is a clamp 30 and freely slideable through the cable is a resilient wire 31 10 connected to the forward end of the control valve by a set screw 32 while at its opposite end, the wire carries a button 33. Thus, this button may be readily grasped for manually shifting the control valve and, in this 15 connection, it is to be observed that the lug 28 upon the arm 27 will limit the valve against forward displacement while the set screw will limit the valve against rearward displacement. 20 Arranged beneath the control valve is an air throttle valve comprising a squared valve body 34 provided at its upper side with a boss 35 and at its lower side with a nipple 36. The nipple 22 of the control valve is 25 threaded into the boss 35 for connecting the valves and slideable through the valve body 34 is a squared air throttle valve 37 limited against displacement by a stop screw 38 threaded through the valve body to project 30 at its inner end into a groove 39 in the adjacent side face of the valve. As best shown in Figure 4, the valve 37 is provided with a plurality of spaced passages 40 of successive graduated diameter while near its forward 35 end the valve is further provided with an air braking passage 41, the valve being movable longitudinally to bring each of these passages into register with the nipple 35 and boss 36 to permit flow of air through 40 the valve. Threaded at one end through the forward end of the valve is a closely wound helical spring 42 the inner end of which is, as shown in Figure 4, closed by a plug 43 so as to prevent flow of air through the 45 spring into the passage 41. At its outer end, the spring is provided with an eye 44 and, as will be perceived, the spring may be adjusted upon the valve for varying the effective length of the spring. Mounted upon the 50 throttle lever 13 of the engine carbureter is a throttle lever arm 45 which, as best shown in Figure 6, is provided with a pair of depending ears 46 snugly embracing the lever, while at its forward end, said arm is provided 55 with an eye 47 through which is engaged a bolt 48 rigidly connecting the arm with the lever. The arm may be stamped from a piece of suitable resilient sheet metal and at its rear end is bent up to form a 60 sleeve 49 in which is clamped one end of a closely wound coil spring 50 extending forwardly over the arm and secured to the forward end of said spring is an eye 51. As will now be noted, the usual cross rod 52 65 of the usual manual throttle control is, in- stend of being engaged directly with the free end of the lever 13, engaged through the eye 51 of the spring 50 and through the eye 44 of the spring 42, being secured against displacement by the usual cotter pin. 70 As will now be understood in view of the foregoing, when the rod 52 is moved endwise by the usual hand lever for opening the carbureter throttle valve or what may well be termed the fuel throttle valve, the rod will 75 pull against the spring 50 in a direction tending to flex the spring longitudinally so that the spring will act upon the arm 45 for swinging the lever 13 to open the valve. Coincidentally, the rod 52 will pull upon the 80 spring 42 shifting the air throttle valve 37 from closed position, as illustrated in Figure 7, when the smaller of the passages 40 will be moved into register with the 85 passages of the valve body 34. Under ordinary conditions, the control valve 34 will be manually set in the manner previously described, to admit hot air therethrough from the heater 18. Accordingly, hot air will be 90 drawn by engine suction, as shall presently be described, through the control valve and through the smaller passage 40 of the air throttle valve. As the opening movement of the fuel throttle valve is continued, the next largest of the passages 40 will be 95 brought into register with the passages of the valve body 34 and so on with each of said passages 40 so that an increased volume of air will be admitted through the air 100 throttle valve as the volume of fuel mixture flowing past the fuel throttle valve is increased, a definite ratio being maintained. When the rod 52 is shifted in the opposite direction for closing the fuel throttle valve, the air throttle valve 37 will, of course, be 105 coincidentally shifted for reducing the volume of air flowing therethrough until, when the fuel throttle valve is closed, as shown in Figure 7, the air throttle valve will also be closed. I accordingly provide an arrangement 110 wherein the fuel throttle and air throttle valves will both be operated simultaneously by a single hand control, the spring 42 providing a flexible connection between the rod 52 and air throttle valve adapted to 115 accommodate the arcuate movement of the forward terminal of the rod while imparting an endwise movement to said valve. 120 Attention is now directed to the fact that by interposing the spring 50 between the rod 52 and arm 45, the rod may be shifted independently of said arm, the spring providing a flexible connection between the rod and arm. Accordingly, after the rod has been moved to close the throttle valve as 125 shown in Figure 7, the rod may, as shown in Figure 8, be further shifted in the same direction for moving the air throttle valve 37 from closed position to open position having the passage 41 registering with the 130

passages through the valve body 34. Thus, by properly setting the control valve 24 to admit cold air therethrough, cold air may, after the flow of fuel mixture has been cut off, be fed to the engine cylinders for cooling the engine while the ensuing compression in said cylinders will serve to brake the engine which, when coupled with the vehicle propeller shaft, will operate to brake the vehicle.

Connected to the valve body 37 is a distributor comprising a relatively thin flat body 53 shaped to fit between the confronting flanges of the manifold 11 and carbureter 12 and formed through the body are openings 54 to accommodate bolts extending between said flanges so that the distributor will thus be secured in place by the fastening elements employed for connecting the carbureter with the manifold. Preferably, suitable gaskets 55 are, as best shown in Figures 7 and 8, arranged at opposite sides of the body so as to form sealed joints with the carbureter and manifold. Formed in the body centrally thereof is an opening 56 registering with the fuel mixture passages of the carbureter and manifold while at one end the body is provided with a nipple 57 into which the nipple 36 of the valve body 34 is threaded for connecting the distributor with the valve. Leading from said nipple into the opening 56 are diverging passages 58 and removably fitting in said opening is a distributor spool 59. As shown in detail in Figure 5, the spool is formed at its ends with radial annular flanges 60 which snugly fit the opening 56 coaxing with the wall thereof to define an annular discharge chamber 61 about the hub of the spool and in communication with the passages 58. The hub of the spool is provided with a plurality of circumferentially spaced openings 62 therethrough and overlying the flanges 60 at the ends of the spool are mixing screens 63. Extending through the screens and through suitable openings in the flanges are fastenings 64 detachably securing the screens in position, the screens and the spool being bodily removable as a unit. As will be seen, the suction of the engine will, when the valves 24 and 37 are open, induce a flow of air through the passages 58 of the distributor into the chamber 61 and thence through the opening 62 between the screens 63 to become mingled with the fuel mixture and drawn through the intake manifold to the engine cylinders, one of the screens tending to initially break up the fuel mixture and the other screen tending to commingle the fuel mixture with the air.

In Figure 9 of the drawings, I have illustrated a slightly modified form of control valve. In this modification, the valve is indicated at 65, this valve corresponding to the valve 24 of the preferred construction.

Formed through the valve is a passage 66 corresponding to the passage 25. The valve is further provided with a passage 67 corresponding to the passage 26. However, the passage 67 instead of opening through one side of the valve and the lower face thereof, opens through one end of the valve and the lower face thereof, the inlet opening 23 of the valve body, as illustrated in connection with the prior embodiment of the invention, being eliminated. Fitting in the outer end of the passage 67 is a curved inlet pipe 68, the function of which is to prevent any objectionable whistling sound by air taken in through the passage.

Having thus described the invention, what is claimed as new is:

1. A device of the character described including a distributor, an air throttle valve for controlling air flow to the distributor, and flexible means for connecting said valve with a fuel throttle to be operated in unison therewith and adapted to permit the air valve to be moved to open position while the fuel throttle is closed.

2. A device of the character described including a distributor, an air throttle valve controlling air flow to the distributor, and a spring for connecting said valve with a fuel throttle to be operated in unison therewith but adapted to permit movement of the air valve to open position while the throttle is closed.

3. A device of the character described including in combination with a fuel throttle control element, a distributor, an air throttle valve controlling air flow to the distributor, flexible means for connecting said element with a fuel throttle, and means for connecting said element with the valve to be operated in unison with the throttle, the first means being adapted to permit shifting of the element to move the valve to open position while the fuel throttle is closed.

4. A device of the character described including in combination with a fuel throttle control element, a distributor, an air throttle valve controlling air flow to the distributor, means for connecting said element with the fuel throttle including a spring, and means for connecting said element with the valve to move in unison with the throttle, the spring being adapted to flex whereby said element may be shifted for moving the valve to open position while the fuel throttle is closed.

5. A device of the character described including in combination with a fuel throttle comprising a lever, and a control element for the throttle, a distributor, an air throttle valve controlling air flow to the distributor, an arm fixed to said lever, a spring connecting said control element with the arm whereby said element may be shifted for swinging the lever and operating

- the throttle, and a second spring connecting said element with the valve whereby the valve will be moved in unison with the throttle, both of said springs being adapted 15
5 to flex whereby the element may be shifted for opening the valve while the throttle is closed.
6. In a device of the character described, the combination of an air heater, a distributor connected therewith, a manually operable valve controlling air flow from the heater to the distributor and movable to a 10 position for supplying cold air to the distributor, and an air throttle valve operable independently of said first mentioned valve 15
20 but in unison with an engine fuel throttle for controlling the volume of air to the distributor.
7. A device of the character described including a distributor, and an air throttle valve operable in unison with an engine fuel throttle for controlling air flow to the distributor, the air throttle valve being independently movable to open position after the fuel throttle is closed. 25

In testimony whereof I affix my signature.

WATSON B. STOCKMAN. [L.S.]
